(57) **CLAIM**

The ornamental design for a brake pad removal tool, as shown and described.

DESCRIPTION

FIG. 1 is an isometric view of a brake pad removal tool showing my new design;

FIG. 2 is a front elevation view of the brake pad removal tool;

FIG. 3 is a rear elevation view of the brake pad removal tool;

FIG. 4 is a right side elevation view of the brake pad removal tool, wherein the left side elevation view is a mirror image; and,

FIG. 5 is a top plan view of the brake pad removal tool, wherein the bottom plan view is a mirror image.

The broken line showing of the handle is provided for purposes of environment and forms no part of the claimed design.
